**SYNCHRONIZING AND PHASING MECHANISMS
FOR FREE PISTON ENGINES**

John G. Macdonald, Goderich, Ontario, Canada

Application October 5, 1956, Serial No. 614,168

4 Claims. (Cl. 123—46)

This invention relates to improvements in internal combustion engines of the "free piston" type, and more particularly to improved synchronizing and phasing mechanisms therefor.

Briefly, engines of the free piston type employ a pair of opposed pistons having their inner ends reciprocating in a power or diesel cylinder and their outer ends which are of enlarged diameter operating in enlarged compressor cylinders at the ends of the power cylinder. On firing the pistons are forced apart and move outwardly compressing air in "bounce chambers" defined between the outer ends of the pistons and the closed ends of the compressor cylinders. At the same time, air is drawn in behind the enlarged outer ends of the pistons through suitable inlet valves into the compressor cylinders. The hot gases in the power or diesel cylinder are exhausted as the pistons reach the outer end of their stroke, and these hot gases are conducted to a reservoir used to feed a gas turbine. On exhaust of the power or diesel cylinder, the energy stored in the compressed air in the bounce chambers serves to return the pistons inwardly to their firing position. The air in the compressor cylinders is then compressed on inward movement of the pistons. Normally the compressed air is delivered to a reservoir from which it is fed into the power cylinder at the completion of the next piston stroke to scavenge the power cylinder.

In order to maintain the opposed pistons in the same relative phase relation, that is, in step, during their reciprocal movement a synchronizing mechanism must be provided and, in the case where two or more cylinder units are employed, e.g. two alternately firing cylinder units, a phasing mechanism must also be provided to keep the pistons of the one cylinder unit in the proper relative phase relation with the pistons in the other cylinder unit or units.

Some present synchronizing mechanisms used on this class of engine use a "cross linkage and rocker arm" between the opposed pistons. The reciprocating mass of the rocker arms tends to cause vibration and their mass imposes a stress on the bearings and other parts of the linkage. In other cases, racks and pinions are used to synchronize the pistons. Since only one or two teeth of the pinion can be engaged with the rack at any given time, wear or breakage of a tooth, as in a fatigue failure, results in serious damage to the engine.

It is the object of this invention to provide a very much simplified synchronizing mechanism that will overcome the problems encountered with previous mechanisms used for this purpose.

In particular, it is the object of the invention to provide a synchronizing mechanism which will in addition to being simple, be compact, easily installed and adjusted, and will eliminate unbalanced stresses on the pistons and moving parts to provide vibrationless piston synchronism.

In the free piston engine, for high engine efficiencies, the objective is to add as little mass as possible to the pistons so that a high piston velocity can be achieved and to convert a minimum of the energy imparted to the

2

pistons on combustion into mechanical energy. It is therefore an important object to provide a synchronizing mechanism which will have low inertial resistance to add a minimum of mass to the pistons and to provide such a mechanism which will have low frictional losses.

As it is desired to use the power delivered from the pistons to the synchronizing mechanism to operate the fuel injection pump, oil pump and other accessories, it is an object to provide a synchronizing mechanism which will convert the high piston velocity to a low velocity in an output member from which the accessories can be conveniently driven.

Again it is an object to provide a synchronizing mechanism as aforesaid which will be strong and durable.

Another important object is to provide an extremely simple phasing mechanism for coaction with the synchronizing mechanisms of a pair of cylinder units, e.g. a pair of alternately firing cylinder units whereby through the synchronizing mechanisms the pair of pistons of one cylinder unit, which are kept in correct relative phase relation by such synchronizing mechanisms, are also kept in correct relative phase relation with the pair of cylinders in the other unit.

According to the invention the means of synchronizing the opposed pistons comprises a pair of rods or plungers, one non-rotatably fixed to each of the opposed pistons and arranged in opposing coaxial relation, the ends of the rods having spiral formations of opposite hand thereon engaging a mating spiral formation on the opposite ends of an intermediate rotatable member coaxial with the rods, which member is maintained against endwise movement while being rotated by the rods as they reciprocate with the pistons to maintain equal rod and hence piston displacement. It will be appreciated that the spiral formations on the ends of the rods may be either male or female and the spiral formations on the ends of the intermediate member will be the reverse.

In the preferred form of the invention, two pairs of such rods and intermediate members are employed, the rods on each piston being disposed in 180° relation to provide equal stress on each piston at opposite sides thereof.

Another feature of the invention resides in utilizing the intermediate rotating member or members as the power source for the fuel injector and other engine accessories.

Still a further feature resides in forming the rod members as hollow members and providing for the air exhaust of these members to eliminate any air cushions which would adversely affect their reciprocation.

Further, according to the invention, the phasing mechanism is driven off the intermediate rotating members of the synchronizing mechanisms of a pair of alternately firing cylinder units and arranged to control the fuel injection into the cylinder units, the phasing mechanism having a neutral position in which it remains during synchronism of the two cylinder units and being displaced from the neutral position on the cylinder units falling out of synchronism in a direction to increase fuel to the lagging cylinder unit or vice versa.

These and other objects and features will become apparent from the following description taken in conjunction with the accompanying drawings, in which:

Figure 1 is a mid-vertical sectional view, partly broken away, illustrating a free piston engine employing a synchronizing mechanism embodying the present invention;

Figure 2 is an end view, partly broken away, of the engine of Figure 1;

Figure 3 is a horizontal sectional view of the engine, partly broken away, showing the pistons at the opposite end of their stroke from that shown in Figure 1;

Figure 4 is an exploded side-elevational view on an enlarged scale and partly broken away showing the components of the synchronizing mechanism;

Figure 5 is an exploded perspective view on an enlarged scale, showing the pistons and the synchronizing mechanism removed from the cylinder unit;

Figure 6 is a view similar to Figure 5, but with the pistons broken away, showing an alternative form of synchronizing mechanism;

Figure 7 is a part-perspective, part diagrammatic view, illustrating the principle of a phasing mechanism according to the invention for correlating from the synchronizing mechanisms the movement of the pistons in two separate cylinder units;

Figure 8 is a fragmentary, mid-vertical sectional detail of an alternative form of spiral drive connection between the reciprocating rods or plungers and the intermediate driven member of a synchronizing mechanism embodying the invention.

With reference to Figures 1 and 3, the cylinder unit generally designated at 1 is made up as in the normal construction of free piston engines of a central power or diesel cylinder 2, which opens at each end to a compressor cylinder 3 which is of larger diameter than the power cylinder, the connection between the cylinders being through flanges 4 and 5. The compressor cylinders 3 are closed at their outer ends by the walls 6, and operating within the cylinder unit 1 are a pair of pistons 7 having their inner ends 8 operating in the power cylinder 2 to define therebetween a central combustion chamber 9, and having enlarged outer ends 10 operating in the compressor cylinders 3.

As shown particularly in Figure 3, the power cylinder 2 is provided with a central surrounding chamber 11 through which a suitable cooling medium may be circulated, and additionally has a surrounding compressed air storage chamber 12 to which communication is had from the power cylinder 2, through ports 13 at the left hand end of the power cylinder, and ports 14 at the right hand end of the cylinder. Also leading from the right hand end of the cylinder are ports 15 in communication with an exhaust passage 16.

In operation, considering the starting position as illustrated in Figure 3 with the pistons 7 forced inwardly to compress the gas or air in the combustion chamber 9 to the ignition point, fuel is introduced into the mixture through a suitable fuel injector 17. On combustion, the pistons are forced apart in opposite directions with the outer ends 10 of the pistons compressing air or gas located between these outer ends and the end walls 6 of the compressor cylinders which define bounce chambers 18 therebetween. This compressed air forms an energy storage medium for returning the pistons to the inner end of their stroke, as shown in Figure 3, upon the exhausting and scavenging of the power cylinder 2.

As the outwardly moving pistons 7 reach the end of their stroke, as illustrated in Figure 4, the right hand piston will have uncovered the ports 15, allowing the escape of the hot pressure gases from the power cylinder 2, which gases are conducted away through the exhaust passage 16 for operating a suitable turbine. The left hand piston, at the outer end of its stroke, uncovers the ports 13 which provide communication from the compressed air storage chamber 12 to the interior of the power cylinder 2, allowing compressed gases from the chamber 12 to enter and scavenge the power cylinder. As the pressure in the power cylinder drops on exhaustion of the hot gases, the energy of the compressed air in the bounce chambers 18 will force the pistons 7 inwardly towards the position of Figure 3, in preparation for the next cycle. During the inward movement of these pistons the enlarged outer piston ends 10 will compress air previously admitted to the compressor cylinders 3 through suitable inlet valves 19 on the outward stroke of the pistons, and reduced intermediate portions 20 and 20'

of the left and right hand pistons define annular passages 21 and 21' which conduct this compressed air through the ports 13 and 14 to the compressed air storage chamber 12.

It will be noted that the reduced portion 20' of the right hand piston is shorter than the left hand piston, and the inner portion 8 of the right hand piston closes the exhaust ports 15, with the pistons forced inwardly to their firing position.

The operation of the engine thus far described is essentially conventional, except that the provision of the reduced intermediate piston portions 20 and 20' eliminate the necessity of having internal valves within the engine, as more fully discussed in my co-pending United States application Serial No. 609,579, now abandoned.

It will be understood that the means of starting the engine and the specific fuel injector system, and other details omitted for sake of clarity may be selected as desired.

The travel of the pistons 7 will depend to a certain extent on their mass and inertia, and the length of the stroke will be dependent upon the amount of fuel injected for given piston and cylinder conditions. Since there will be inherent differences in the pistons, a synchronizing mechanism must be provided to maintain the piston movement of the opposed left and right hand pistons exactly equal and opposite for engine operation. The synchronizing mechanism employed according to one form of the invention is best seen in Figures 1, 4 and 5. As illustrated, attached to the inner face of the enlarged outer ends 10 of each of the pistons 7 are rods or plungers 22. Preferably, there are two rods attached to each piston, with the rods being disposed in 180° relation. These rods project inwardly of the cylinder unit parallel to the inner piston portions 8, the inner or free ends of the rods projecting through suitable bushings 23 mounted in the flanges 4 of the power cylinder 2.

The rods 22 are preferably hollow, and are provided with ports 24 affording communication between the interior of the rods and their respective compressor cylinders. The rods are anchored to the pistons so that they will be secure from rotation by having their attached ends serrated as at 25, and anchored by the serrations in suitable bushings 26 cast in the piston portions 10. The outer ends of the rods 22, which operate outside of the compressor cylinders, are provided with spiral or helical drive formations thereon which may be either male or female. The arrangement of the pistons and rods is such that the rods of the left hand pistons are disposed coaxially with the rods of the right hand pistons; that is, corresponding rods at each side of the power cylinder are coaxial.

Extending between the bushings 26 of the coaxial left and right hand rods are tubular members 28 disposed, in turn, coaxially with the respective coaxial rod pair. Each of the tubular members 28 is provided with spiral drive formations 29 and 29' to engage respectively with the spiral drive formation 27 on the ends of the left and right hand rods of the coaxial rod pair respectively.

It will be understood that the spiral drive formation 27 of the left hand rods will be of opposite hand to that of the right hand rods, and therefore, the spiral or helical drive formations 29 and 29', which will be complementary, respectively, to the spiral drive formations of the left and right hand rods, will also be of opposite hand.

By employing the two sets of coaxial plungers and intermediate tubular members 28 on opposite sides of the power cylinder, a balanced piston operation will be provided by the synchronizing mechanism.

In operation, it will be understood that as the pistons reciprocate, thereby reciprocating the rods of plungers 22, these rods operating in the tubular intermediate driven members 28 will rotate these members through the engaging complementary drive formations, first in one direction and then in the opposite direction, the opposite

hand of the left and right hand spiral formations providing the rotational force from the rods of both pistons always in the same direction.

It will be seen from Figure 1 that the rods 22 remain in telescopic engagement with the intermediate members 28, even at the outer ends of their strokes, and the complementary spiral or helical drive formations 27 and 29 and 29', respectively, remain in engagement. Thus the rate and extent of travel of each piston is governed by the rotational oscillation of the intermediate members 28, and as these members are held from axial movement, the movement of the left hand piston must therefore be precisely equal and opposite to the opposed right hand piston. While the intermediate driven members 28 are maintained against axial displacement during operation of the synchronizing mechanism, it may be adjusted axially as a preset adjustment through the use of shims, as indicated at 30 to adjust the position of the pistons relative to the power cylinder.

In operation, the inward movement of the rods 22 into the tubular members 28 will produce a compression of the air in these members, and this compressed air will escape through the ports 24 into the compressor cylinders, so that there will be no abnormal pressures within the members 28 or the rods. Suitable gasket bushings 31 between the bushings 26 and the tubular members ensure against leakage of pressure air from the compression cylinders to the atmosphere, as well as supporting members 28.

It will be noted that both the tubular members 28 and the rods 22, by virtue of being hollow, will provide a minimum of weight while affording strength. Thus the synchronizing mechanism is strong and durable, while holding the additional mass added to the pistons to a minimum, and providing low inertial resistance.

Because of the long lead of the helical or spiral drive formations, the intermediate members 28 form relatively slow speed oscillating members suitable for driving the oil pump, fuel pump and other accessories, not shown. These members therefore are provided with drive pinions 32 engaging suitable accessory drive gears 33. Preferably the accessory drive is taken off both of the members 28 to maintain a balance in the load on the pistons at opposite sides of the power cylinder.

Figure 6 illustrates a modified form of the invention, in which the plungers 22' secured to the pistons 7 are hollow and have an internal spiral formation 34 adapted to cooperate with complementary spiral drive formations 35 on the ends of a coaxial intermediate shaft 36, mounted against axial movement in a suitable bearing 37. It will be understood, of course, that the spiral or helical formation on the left hand rod 22' will be of opposite hand to that on the right hand rod 22' and correspondingly on the left and right hand ends of the shaft 36. Thus, in operation, with the ends of the shaft 36 telescoped into the ends of the plungers 22' inward movement of the plungers will produce a rotation of the shaft 36 in one direction, and outward movement of the plungers will produce a movement of the shaft in the opposite direction.

Again, the intermediate member of the synchronizing mechanism, comprising in this case the shaft 36, serves as a source of power for operating the accessory equipment of the engine, and to this end, there is mounted on the shaft 36 a pinion 38 engaging with a gear 39, driving shaft 40, to which the accessories may be connected.

While the spiral drive formations so far described are shown as helical rib and groove formations, anti-friction spiral drive formations may also be employed as illustrated in Figure 8, which is more or less diagrammatic. In this case, a ball bearing screw assembly is used in which the "screw" comprises a rod or plunger 41 corresponding to the rod or plunger 22, having a spiral formation 42 thereon. The intermediate driven member 43 has at each end thereof, to cooperate with the respective plunger 41 (one plunger and one end only being shown),

a "nut" 44, having a spiral formation 45 formed therein. The spiral formations 42 and 45 form concave helical ball races, and the end 44 of the member 43 is filled with steel balls 46, and is provided with a tubular ball guide 47 which interrupts the path of the balls to deflect them from the helical race, guides them diagonally across the outside of the nut, and leads them back again into the raceway.

It will be understood that the actual construction of 10 the anti-friction spiral drive, in itself, is not new to the applicant, and is currently manufactured, but the application of such an anti-friction device in a free piston engine synchronizing mechanism comprises a new application of this principle.

15 It will be understood that in a free piston engine there will be the necessity of maintaining the proper phase relation between the pistons of different cylinder units where two or more cylinder units are incorporated into the engine. The reciprocating rotational motion of the 20 intermediate driven members 28 lends itself to the provision of a simple phasing mechanism to correlate the movement of the pistons of the separate cylinder units as illustrated, more or less diagrammatically, in Figure 7.

In this case, it will be seen that driven from the pinions 25 32 of the intermediate driven members 28 of the synchronizing mechanisms of two adjoining cylinder units, indicated as at 48 and 48' which correspond to the cylinder unit 1, are sector gears 49. These sector gears rock shafts 50 carrying cranks 51 connected by links 52 to a 30 cross bar 53. Projecting from the cross bar 53 is an arm 54 on the free end of which is journaled a control bar 55 suitably connected in any desired manner to control the fuel injection to or the compression in the bounce chambers of the two cylinder units 48 and 48'.

35 Alternatively, the bar 55 may be connected to control a combination of the fuel injection and bounce cylinder compression as will be apparent to those skilled in the art.

It will be seen that if the pistons of the cylinder units 40 48 and 48' have precisely the same travel and maintain their relative phase, which will normally be 180° out of phase, then the rock shafts 50 will rotate precisely the same amount, and the left hand end of the cross bar 53 will be displaced exactly the same amount as the right hand end and the centre of the cross bar will remain stationary; that is, the arm 54 will remain stationary as will the control bar 55. However, should the pistons move out of their predetermined phase relationship, this will result in one of the rock shafts being turned a different 45 amount from the other, and one end of the cross bar 53 will be moved more than the other so that the central portion must be displaced up or down as the case may be, moving the arm 54 and control rod 55. This movement 50 will effect the fuel injection into, or the compression in the bounce chambers of the cylinder units, and the control will be such as to alter the respective control parameters in a manner to restore the desired out of phase relationship between the pistons of the two cylinder units.

It will be understood that the synchronizing and phasing mechanisms herein illustrated are by way of example only, and alterations and modifications in the details and constructions thereof may be made without departing from the spirit of the invention as set forth in the appended claims.

65 What I claim as my invention is:

1. In an internal combustion engine a power cylinder defining centrally a combustion chamber, a compressor cylinder of greater diameter than said power cylinder arranged at each end of said power cylinder and having 70 a closed outer end, opposed pistons having inner portions disposed to reciprocate in said power cylinder and enlarged outer portions disposed to reciprocate in said compressor cylinders, and means to provide equal and opposite synchronized movement of said pistons, said 75 synchronized means comprising a pair of rods non-rotat-

ably secured to the enlarged outer portions of each of said pistons on opposite sides of the piston and projecting parallel to and in the direction of the inner portion of the piston said rods operating through openings in the compressor cylinders and the rods secured to the one piston being arranged coaxial with the rods of the other piston to form coaxial rod pairs, the projecting ends of said rods having spiral drive formations thereon with the spiral drives of the rods secured to the one piston being of opposite hand to the spiral drives of the rods secured to the other piston, and a rotatable driven member arranged coaxially between each pair of coaxial rods and in telescopic engagement with the projecting ends thereof, each of said driven members having spiral formations at each end thereof complementary to and in driving engagement with the spiral formations on the rod ends with which said members telescopically engages whereby reciprocation of said rods on piston reciprocation produces a rotational oscillation of said driven members, said driven members being independently axially adjustable, and means maintaining said driven members in axially adjusted positions against movement axially of said rods.

2. In an internal combustion engine of the free piston type having a pair of opposed pistons mounted for reciprocation towards and from each other in a power cylinder, synchronizing means to provide equal and opposite synchronized movement of the pistons, said synchronizing means comprising at least one pair of opposite rods, one rod of the pair being non-rotatably fixed to one of said pistons and the other rod being non-rotatably fixed to the other piston, said rods being co-axial and adapted to move axially towards and from each other on piston reciprocation, said rods having spiral drive formations on their adjacent ends, with the spiral formation on the end of the one rod being of opposite hand to the other, 35

and a rotatably driven member arranged co-axially between said rods and in telescopic engagement with the adjacent end thereof, said driven member having spiral formations complementary to and in driving engagement with the spiral formations on the ends of said rods, whereby reciprocation of said rods on piston reciprocation produces a rotational oscillation of said driven member, said driven member being axially adjustable, and means maintaining said driven member in adjusted axial position against movement axially of said rods.

5. A device as claimed in claim 2 in which said rods are hollow and said spiral rod drive formations comprise internal splines and said driven member comprises a shaft and said complementary driven member spiral formations comprise external splines formed on the ends of said shaft.

10. A device as claimed in claim 2 in which said spiral drive formations in said rods and said complementary spiral drive formations on said driven member are in driving engagement through a series of balls arranged to circulate between said complementary drive formations.
